[57] CLAIM

The ornamental design for an electrical junction box, as shown and described.

DESCRIPTION

FIG. 1 is an isometric view from above and one end of the electrical junction box showing my new design;

FIG. 2 is an isometric view from below and the other end thereof;

FIG. 3 is a bottom elevation view thereof;

FIG. 4 is a side elevation view thereof; the other side being identical; and,

FIG. 5 is an end elevation view thereof, the other end being identical.
